Primary Examiner — Michael A. Pratt*Assistant Examiner* — Adam C Mager(74) *Attorney, Agent, or Firm* — Ulmer & Berne LLP;
Brian Turung; Eric Robbins(57) **CLAIM**

The ornamental design for a sailboat, as shown and described.

DESCRIPTION

FIG. 1 is a front view of a sailboat, showing the new design; FIG. 2 is a bottom view of the sailboat; FIG. 3 is a rear view of the sailboat; FIG. 4 is a right side view of the sailboat; FIG. 5 is a top view of the sailboat; and, FIG. 6 is a front top perspective view of the sailboat. The portions of the boat shown in broken lines form no part of the claimed design.

1 Claim, 6 Drawing Sheets(56)
